GOLF PUTTER

Thomas Albert Hamilton, Hale, England

Application December 31, 1936, Serial No. 118,642
In Great Britain January 21, 1936

2 Claims. (Cl. 273—80)

This invention relates to golf ball putters as used on the greens of golf courses wherein the control of the club for making putts of different length is usually effected by altering the position of the hands on the handle portion of the club, that is to say, for the shorter putts the hands are placed lower down the handle thereby leaving an unwieldy and unbalanced length, longer or shorter according to the length of putt, of shaft above the hands which decreases the golfer's control of the club and consequently his efficiency at the game.

The object of the present invention is to provide a golf ball putter which can be adjusted in the course of play to the effective length desired without materially disturbing the balance and whilst maintaining the required balance without altering the position of the hands of the user on the handle.

Whereas the standard golf ball putter has a shaft of fixed length, according to the present invention putter shafts are formed in two or more parts (usually two) sliding telescopically one within the other adapted to frictionally engage each other and provided with spring means to position the parts relatively to each other in a plurality of adjusted positions, provision being made to prevent any angular movement of the telescopic members relatively to each other about their common axis such provision conveniently comprising a tube or bar of square or other non-circular shape in cross section rigidly fixed to one sliding element and passing through a guide of corresponding cross sectional shape in the other element such an arrangement serving also to increase the lateral rigidity of the shaft.

Spring means are preferably provided to retain the sliding element in the adjusted position.

The invention will be more particularly described by the aid of the accompanying drawing wherein the same reference letters or characters relate to the same thing or part and in which:—

Figure 1 is an external view of a putter constructed according to the invention shown in the extended position whilst

Figure 2 is a longitudinal sectional view taken from the rear.

Figure 3 is an enlarged cross sectional view on the line 3—3, Figure 2,

Figure 4 is a view corresponding to Figure 1 but showing the club shortened and as ready for use in making short putts and

Figure 5 is a detail longitudinal section of the middle part of a club showing a modified method of mounting the locking springs and

Figure 6 is a plan view of the spring mounting means detached.

Figure 7 is a view of the top part of a club constructed according to the invention showing further modified locking means.

In carrying the invention into effect according to one convenient manner as illustrated in Figures 1 to 4 the improved club comprises a tubular portion *a* constituting the handle, provided with any suitable form of grip, such as the leather wrapping *b*, the cylindrical lower portion *a*¹ of which has an internal diameter corresponding to the external diameter of the cylindrical top portion *c*¹ of the tubular lower portion *c* of the shaft which at its lower end is adapted to fit into the socket *d*¹ of the head *d* of the club. A cap or plug *e* is provided for the top of the handle and rigidly secured thereto is a steel or other metal rod *f* of square shape in cross section formed with cross slots *f*¹, *f*¹ at a predetermined distance apart.

The top end of the cylindrical shaft section *c*¹ is pressed in to form a square cross section at *c*² to receive the metal rod *f* and spring tongs *g* surrounding the same, a diametrically opposite pair of which is formed with indentations *g*¹ adapted to engage the cross slots *f*¹ so as to positively lock the parts in the adjusted position. Said springs *g* are retained in position by splaying the lower ends *g*² outwards and forming protuberances *g*³ thereon to engage the bottom and top portions of the squared end *c*² respectively of the shaft section *c*¹ as will be clearly seen on reference to Figure 3. The springs *g* constitute a lining for said squared shaft end *c*², with which the metal rod *f* forms a good sliding fit. The inner end of the rod *f* is provided with a projection in the form of a stud *f*² which is placed in position when assembling the parts through the hole *c*³ in the shaft section *c*¹ to limit the outward movement or extension of the handle *a* on the shaft *c*.

It will now be seen that with a club head *d* resting on the ground sufficient pressure on the handle *a* in the longitudinal direction will cause the spring catches *g*¹ to yield and allow said handle *a* to telescope on the shaft portion *c*¹ to the desired extent according to the length of the putt it is desired to make as governed by the desire of the golfer said spring catches engaging one of the sets of notches or cross slots *f*¹ in the adjusted position whilst the construction of the club is such that no relative longitudinal or angular movement between the top and bottom portions of the club takes place in use. Said shortening of the shaft can be effected whilst the hands

are on the handle using the ordinary grip for putting and when it is desired to extend the club the hands are still retained in position and the foot is placed on the head to assist the pull.

5 Instead of forming a square at the top of the section c^1 said top may be left round and a metal fitment h brazed or otherwise rigidly secured near the top end of the cylindrical portion of the shaft element c and internally of the 10 same, see Figures 5 and 6, said fitment h having diametrically opposite longitudinal slots h^1, h^1 , formed on the exterior to receive spring tongs i, i having fingers or extensions i^1, i^1 adapted to frictionally grip the bar f on opposite sides 15 and having the top end bent to form projections i^2, i^2 to engage the cross slots f^1, f^1 formed in the bar f at predetermined distances apart so as to positively lock the parts in the adjusted position, the bar f being secured to the handle 20 part b which is constructed and mounted as in the last example. In this case the lower part of the rod f is provided with a collar f^3 which forms a sliding fit for the internal bore of the cylindrical shaft portion c^1 to limit the outward 25 movement or extension of the handle a on the shaft c as does the stud f^2 in the preceding example, the shortening and lengthening of the club being effected in like manner.

According to the modified construction shown 30 in Figure 7 the spring locking tongs g and i are dispensed with and the end of the handle portion a is slotted at k so as to engage the tubular portion c^1 of the upper part of the shaft c with a springy friction grip capable of yielding 35 sufficiently to allow the protuberances l formed by indentations near the end of the handle portion to spring into and out of engagement with the recesses c^3 formed in the cylindrical portion c^1 of the shaft c . The handle portion may 40 be provided with a square rod to slidably fit a square hole in the top of the shaft section c^1 as in the preceding examples.

Whilst the shaft and handle are preferably made round in cross section they may be of

square, octagonal or other non-circular shape in cross section.

By these means a golf ball putter is provided which can be adjusted in the course of play to the effective length desired without materially disturbing the balance and whilst maintaining the required balance without altering the position of the hands of the user on the handle. 5

Having now particularly described and ascertained the nature of my said invention and in 10 what manner the same is to be performed, I declare that what I claim is:—

1. A golf ball putter which can be adjusted during the course of play to the effective length desired without altering the position of the hands 15 of the user on the handle, comprising a head, a tubular shaft with a cylindrical portion, attached to said head, a tubular handle slidably mounted on the cylindrical portion of the shaft, a non-circular bar rigidly attached to said handle, and provided with transverse notches, a guide at the top of the shaft having a through bore of a shape corresponding to the cross sectional shape of the bar and spring fingers secured to the shaft adapted to engage said notches 20 to lock the bar in the adjusted position.

2. A golf ball putter which can be adjusted during the course of play to the effective length desired without altering the position of the hands 30 of the user on the handle, comprising a head, a tubular shaft with a cylindrical portion, attached to said head, a tubular handle slidably mounted on the cylindrical portion of the shaft, a non-circular bar rigidly attached to said handle, and provided with transverse notches, a 35 guide at the top of the shaft having a through bore of a shape corresponding to the cross sectional shape of the bar, spring fingers secured to the shaft adapted to engage said notches to lock the bar in the adjusted position and means 40 to limit the outward longitudinal movement of the handle on the shaft.

THOMAS ALBERT HAMILTON.
